UNITED STATES PATENT OFFICE.

WILLIAM HENRY FARRIS, OF ROCK ISLAND, ILLINOIS.

STEAM-GENERATOR.

SPECIFICATION forming part of Letters Patent No. 364,403, dated June 7, 1887.

Application filed February 9, 1887. Serial No. 927,030. (No model.)

To all whom it may concern:

Be it known that I, WILLIAM HENRY FARRIS, of Rock Island, in the county of Rock Island and State of Illinois, have invented a certain new and useful Improvement in Steam Generators, Circulators, and Pulsators; and I do hereby declare the following to be a full, clear, and exact description of the invention, such as will enable others skilled in the art to 10 which it appertains to make and use the same.

My invention relates to an improvement in steam-generators.

In Letters Patent No. 349,426, granted to me on the 21st day of September, 1886, a hollow bridge-wall was shown and described, the interior of which was provided with chambers having a direct communication with each other. A set of hollow grate-bars were removably secured to the bridge-wall by compression-joints, and hollow side bars, also connected with the bridge-wall by compression-joints, led from the bridge-wall along the sides of and within the fire-box to the water and steam portions of the boiler, one of the said side bars serving as a conduit for leading the water from the boiler to the bridge-wall, and at the same time as a steam-conduit for returning any steam which might be generated therein or back up from the bridge-wall therein 25 to the steam portion of the boiler through a branch pipe, and the other side bar serving as a steam-discharge and steam-generating pipe only.

The object of my present invention is to 35 simplify the construction and arrangement of the bridge-wall and conducting-pipes for the purpose of adapting them to use in connection with all forms of boilers, and for rendering the circulation of the water and generation of 40 steam more rapid and uniform.

A further object is to provide a bridge-wall of increased height and of such form that the bars which conduct the steam from the steam-chamber of the bridge-wall to the boiler shall 45 occupy positions within and along the sides of the fire-space at a considerable distance above the grate-bars, for the particular purpose of burning wood to advantage.

With these ends in view my invention consists in a bridge-wall provided with a water-receiving and steam-discharging chamber communicating with each other only through the

hollow grate-bars and tubes leading from one of the bridge-wall chambers therein, in connection with a water-conducting pipe leading from the 55 water-space of the boiler to the water-receiving chamber of the bridge-wall and a steam-conducting pipe leading from the steam-discharging chamber of the bridge-wall to the steam-space of the boiler.

My invention further consists in a sectional bridge-wall, the lower section of which is provided with a water and a steam chamber, and the upper section of which is provided with a steam-chamber in communication with the 65 steam-chamber of the lower section and with the steam-space of the boiler.

My invention further consists in certain features of construction and combinations of parts, as will be hereinafter described, and pointed 70 out in the claims.

In the accompanying drawings, Figure 1 is a top plan view, partly in section, showing one form of hollow bridge-wall, the side conveying and return pipes, and the hollow grate-bars, the rear portion of the boiler being broken away. Fig. 2 is a front elevation of the same. Fig. 3 is a side elevation of the same with a portion of the fire-pot wall broken away. Fig. 4 is a longitudinal vertical section through line *x* *x* of Fig. 1. Fig. 5 is a transverse vertical section through line *y* *y* of Fig. 1. Fig. 6 is a partial side elevation of the grate-bars and steam-conducting pipes, showing the wood-burning bridge-wall 85 in end elevation. Fig. 7 is a vertical section of the wood-burning bridge-wall, taken transversely through its central portion. Fig. 8 is a vertical section taken longitudinally through the center of the wood-burning bridge-wall. 90 Fig. 9 is a view of the compression-joint, showing its parts in detail. Fig. 10 is a view in longitudinal vertical section, showing the adaptation of the generating grate-bars to a locomotive or marine engine. Fig. 11 is a transverse 95 vertical section of the locomotive or marine boiler through the line *z* *z* of Fig. 10, and Fig. 12 is a detached view of one form of loose joint.

A represents a boiler of ordinary construction; *B*, a grate; *C*, a bridge-wall, and *a* the furnace-wall.

The form of bridge-wall shown in Figs. 1 to 5, inclusive, is a simple and economical form,

adapted to use in connection with coal-burning furnaces.

The form of bridge-wall adapted to wood-burning, or to both wood-burning and coal-burning, furnaces is, however, the one which I propose to consider the preferred form in my present application; and since it consists broadly in an auxiliary steam-chamber coupled onto the steam-chamber shown in my former patent, I shall describe it after I have described the form shown in the first five figures.

A pipe, a^2 , leads from the boiler from a point below the water-line, and preferably from the end over the doors opening into the fire-box, 15 and extending partially across the end to one side of the furnace-wall, leads along outside of the fire-box, and preferably outside of the furnace-wall to a point opposite the end of the bridge-wall, where it turns and enters the end 20 of the bridge-wall, thereby forming a conduit for the water to flow from the boiler into a chamber within the said bridge-wall.

The pipe a^2 is provided at convenient points with a stop-valve, D, for shutting off the water 25 in case of accident or for repairs or other purpose, and with a check-valve, d, to prevent the water from setting back and interfering with the flow from the boiler.

The interior of the bridge-wall C, Figs. 1 to 30 5, inclusive, is separated by a suitable partition, e, into two chambers, c' and c^2 , which preferably extend nearly its entire length, and, for convenience, are arranged one in front of and above the other. The lower chamber, c^2 , 35 is the one which the pipe a^2 enters, and which, through the pipe a^2 , is supplied with water from the boiler.

The grate-bars B consists of tubes provided with curved faced transverse grate-lugs b on 40 their upper sides. They are preferably of taper form, as shown, and the grate-bars are open at their ends adjacent to the bridge-wall and closed at their opposite ends. Their ends adjacent to the bridge-wall are re-enforced, as 45 shown at b' , and provided with annular grooves b^2 , the outer portions of the grooves being bell or funnel shaped in cross section, as shown at b^3 .

The lower portion of the bridge-wall is provided with a series of bosses, c^3 , surrounding 50 openings c^4 into the chamber c' at such intervals as separate the grate-bars, and the ends of the bosses c^3 are provided with annular grooves c^5 , adapted to register with and having the same form as the grooves b^2 in the ends of the grate-bars. The joint between the grate-bar and the boss c^3 is formed by a ring or thimble, E, of double convex shape in cross-section, its opposite edges being constructed to 55 enter the grooves b^2 c^5 , but not touch the bottoms of the grooves, thereby insuring a tight joint between the ring or thimble and the walls of the grooves, even though the grate-bars be tilted out of line.

60 The grate-bars B are drawn toward the bridge-wall and the ring or thimble E compressed between them by rods F, provided

with heads f and squared portions f' , near the heads. The squared portions f' are adapted to rest in angular or dovetail slots g, formed 70 in the faces of lugs G, located in the openings c^4 , with the heads f in engagement with the sides of the lugs G, while the opposite ends of the rods project through the closed ends of the grate-bars, and are threaded to receive 75 draw-nuts f^2 .

The contact-faces of the nuts f^2 are rounded, as shown at f^3 , and engage concave seats f^4 in the ends of the bars, whereby the grate-bar is allowed to tilt without opening the joint or 80 straining the parts. The free ends of the bars B are provided with projections b^4 , adapted to engage a movable shoe or rest, H, in a slot, h, the shoe being supported upon a suitable offset, I, or in any other well known or approved 85 manner.

The construction is such that when it is desired to remove a grate-bar for any purpose the shoe H may be slid toward the end of the grate-bar until it clears the offset I, and the 90 end of the bar be then dropped below the said offset, and withdrawn through the ash-pit door or other suitable opening.

The chamber c^2 in the bridge-wall communicates with the interior of the grate-bars 95 through tubes K, which are set firmly in the wall of the chamber c^2 , and extend thence through the openings c^4 , and along the interiors of the grate-bars to points near the closed ends of the said bars.

The water from the chamber c^2 flows into the hollow grate-bars through the tubes K. It is there converted more or less rapidly into steam, which escapes from the grate-bar into the chamber c' , and thence through suitable 100 conducting-pipes to the boiler above the water-line, as follows: On the opposite sides of the fire-box, and within it, are located steam-conducting tubes L, which extend from the bridge-wall on an upward incline to and through the 105 end furnace-wall, thence to the right and left, as shown at l, thence upwardly, as shown at l', and thence toward each other, as shown at l'', uniting with a common inlet-pipe, M, entering the boiler above the water-line. The 110 changes in direction which conducting-pipes L, l, l', and l'' assume are conveniently made by the ordinary L and T shaped bends; but may be made, if found desirable in any instance, by bending the pipe itself. To prevent the backset of steam from the boiler, a 115 check-valve, N, is inserted in the inlet-pipe M.

A blow-off pipe, O, provided with a stop-valve, o, is attached to a portion of the pipe l, l', &c., preferably at a point where it makes 120 its turn upwardly. This is conveniently accomplished by placing a T-connection at the bend, as shown. The ends of the tubes L, adjacent to the fire-bridge, are connected to the bridge by compression-joints m, in a manner quite similar to that hereinbefore explained 125 with reference to the attachment of the grate-bars to the bridge-wall.

The rods m', which hold the tubes L pressed

toward the bridge-wall, are constructed similar to the rods F, and have their squared portions m^2 let into angular slots in lugs n , formed in the outer sides of the openings p , 5 through the bosses P. Their heads m^3 engage the sides of the lugs, and their opposite ends project through the T-coupling n^2 , outside of the wall, where they are provided with rounded-faced nuts m^4 , adapted to engage con- 10 cave seats m^5 in the outside of the couplings.

In the preferred construction of bridge-wall, (represented in Figs. 6, 7, and 8,) a detachable hollow upper section is provided with a steam-chamber, C, communicating with the steam-chamber c' of the lower section through openings S S', formed, respectively, in the bottom of the upper section and top of the lower section at their central portions. The openings S S' are surrounded by bosses having annular 15 grooves in their faces, in which a ring-coupling is inserted similar to that hereinbefore described. Within the opening S in the bottom of the upper section a recessed lug, s, is located to form a seat for the head and stem 20 of the coupling-bolt s' , which projects thence downwardly through the chamber c' , and is provided with a nut, s^2 , on its lower end, which serves to draw and lock together the two sections of the bridge-wall. The upper section, 25 30 C², of the bridge-wall has a rearward tilt from the top of the lower section, and the steam-conducting tubes L lead from it at points near its top and ends. The recessed faced lugs G in the openings leading to the grate-bars are 35 here set with their faces upright instead of horizontal, and the circulating-tubes extend along just below or partially in front of the recesses in the lugs, and thereby serve to prevent the displacement of the rods while the 40 45 50 55 60 65 70 75 80 85 90 95 100 105 110 115 120 125 130 135 140 145 150 155 160 165 170 - therefrom into the interiors of the hollow grate-bars, of a water-conducting pipe leading from the boiler to the water-receiving chamber of the bridge-wall and a steam-conducting pipe 5 leading from the steam-discharging chamber of the bridge-wall to the boiler, substantially as set forth.
3. In a steam-generator, the combination, with a boiler, a bridge-wall provided with a water-receiving and a steam-discharging chamber, and hollow grate-bars, through which the chambers in the bridge-wall communicate with each other, of a water-conducting pipe leading from the boiler to the bridge-wall outside of the fire-space and a steam-conducting pipe leading from the bridge-wall to the boiler, substantially as set forth.
4. In a steam-generator, the combination, with the boiler and the bridge-wall provided 20 with a water-receiving and a steam-discharging chamber, communicating with each other through the hollow grate-bars, of a water-conducting pipe leading from the boiler to the bridge-wall outside of the fire-space and a steam-conducting pipe leading from the bridge-wall to the boiler and passing through the fire-space, substantially as set forth.
5. In a steam-generator, the combination, with the bridge-wall with its water-receiving 30 and steam-discharging chambers, of the water-conducting pipe leading from the boiler to the bridge-wall outside the fire-space and the steam-conducting pipes leading from the bridge-wall to the boiler along the sides of 35 and within the fire-space, substantially as set forth.
6. The combination, with the steam-generating grate-bars and the bridge-wall with its water-chamber and its steam-chamber, of the 40 independent water-conducting pipe and the steam-conducting pipes leading from separate points of the steam-chamber and uniting in a common steam inlet pipe, substantially as set forth.
- 45 7. The combination, with the steam-generating grate-bars and the bridge-wall with its water-chamber and its steam-chambers, of the independent water-conducting pipe with its stop-valves and check-valves, the steam conducting and generating pipes communicating

freely with each other, and having a common steam-inlet pipe leading to the boiler, and the check-valve located in the common steam-inlet pipe, substantially as set forth.

8. The combination, with the steam-conducting tubes leading from the steam-chamber of the bridge-wall through the fire-space and thence to the boiler, of the compression-joints between the tubes and the bridge-wall, the draw-rods for tightening the joints, the slotted 60 lugs located at the sides of the openings into the steam-chamber, and the draw-rods with their heads and squared portions adapted to engage the lugs, substantially as set forth.

9. A steam-generating bridge-wall consisting, essentially, of a lower hollow section and an upper hollow section, the sections being connected together in a slightly tilting or rocking adjustment by a steam-tight joint, substantially as set forth.

10. The bridge-wall consisting, essentially, of the rearwardly-tilting hollow upper section and the two-chambered lower sections, the two sections communicating with each other and being detachable from each other, substantially as set forth.

11. A steam-generating bridge-wall composed of hollow sections united by a steam-tight compression-joint, through which the sections communicate with each other, substantially as set forth.

12. The combination, with the lower section of the bridge-wall with its water and steam chambers and the hollow grate-bars communicating with the steam-chamber direct and 85 with the water-chamber through a circulating-tube, of the upper bridge-wall section with its auxiliary steam-chamber in communication with the steam-chamber of the lower section and the steam-conducting pipes leading from 90 the steam-chamber in the upper section to the boiler, substantially as set forth.

In testimony whereof I have signed this specification in the presence of two subscribing witnesses.

WILLIAM HENRY FARRIS.
